DESIGN FOR A SCARF

Peter Delich, Duluth, Minn.

Application June 1, 1937, Serial No. 69,635

Term of patent 14 years

To all whom it may concern:

Be it known that I, Peter Delich, a citizen of the United States, residing at Duluth, in the county of St. Louis and State of Minnesota, have invented a new, original, and ornamental Design for a Scarf, of which the following is a specification, reference being had to the accompanying drawing, forming part thereof.

The figure is a perspective view of a scarf, showing my new design.

I claim:

The ornamental design for a scarf, as shown.

PETER DELICH.
